UNITED STATES PATENT OFFICE.

WILLIAM PIERCE COWLES, OF MINNEAPOLIS, MINNESOTA, ASSIGNOR OF ONE-HALF TO
SCOTT F. EVANS, OF MINNEAPOLIS, MINNESOTA.

REINFORCED-CONCRETE BUILDING.

1,078,575.

Specification of Letters Patent.

Patented Nov. 11, 1913.

Application filed November 26, 1910. Serial No. 594,381.

To all whom it may concern:

Be it known that I, WILLIAM PIERCE COWLES, of Minneapolis, county of Hennepin, and State of Minnesota, have invented 5 certain Improvements in Reinforced-Concrete Buildings, of which the following is a specification.

This invention relates to improvements in building construction of reinforced concrete 10 and the objects I have in view are to provide a building in which reinforced flat slabs constituting the floors of the building are formed integrally with reinforced concrete supporting columns, and are reinforced by brackets within the said flat slabs and radiating from the column centers and by which the tension and shear stress are carried.

The invention consists generally in the 20 constructions and combinations hereinafter described and particularly pointed out in the claims.

In the accompanying drawings forming part of this specification, Figure 1 is a vertical section through a portion of a flat slab and supporting column, the right-hand half shown in section so as to show clearly the arrangement of the reinforcing rods. Fig. 2 is a plan view, showing the arrangement 30 of the column rods, the brackets, and the rings. Fig. 3 is a plan view showing the complete arrangement of the slab rods and their relation to the columns and brackets.

In all of the drawings, 2—2 represents the 35 column rods, which extend vertically through the building, said rods being formed in suitable sections or lengths, and said sections being arranged in line with one another, and if preferred being provided with suitable means for securing the 40 sections together. A rod, or wire, 3 is preferably wound spirally around the series of column rods, and said column rods and the spirally arranged enveloping rods are 45 embedded in concrete in the usual manner, thereby forming a reinforced column of any suitable size and of any desired strength.

At the line of the floor slab I prefer to provide a series of radiating brackets 4, each 50 bracket being formed of a substantially U-shaped rod with out-turned ends 5 and 6.

These brackets are arranged to project radially from the column centers with the two branches of the U in a substantially 55 vertical plane and with the out-turned ends

projecting downward and upward in the center of the column. I have shown in Fig. 2 of the drawings eight of these brackets, but a greater or less number may be used. They may be of any suitable lengths and widths and formed of rods of any suitable size. Each of the rods 5 and 6 is shown projecting lengthwise of the column, a distance substantially equal to the thickness of the floor slab, but this distance may be increased or diminished as found desirable. The vertically extending rods 5 and 6 are brought together in the central portion of the column and are surrounded by rings 7. I prefer also to surround the column rods 70 by rings 8 arranged above and below each of the brackets 4, and I also prefer to provide a winding of wire 9 around the members of each bracket, as shown in Fig. 1 of the drawings. Within the U-shaped bracket 75 and at the outer end thereof, I provide a large ring 10, preferably formed of a rod bent into a circular figure as shown in Fig. 2 of the drawings, with its ends overlapping and lashed together by wires 11. Any other suitable means for securing the ends of the rings may be employed in place of that herein shown and described. I also prefer to provide on top of the series of brackets 80 an additional ring 12. This ring is preferably arranged to cross the bracket at or near its outer end. I may also provide an intermediate ring 13 preferably arranged at about the middle of the brackets and also preferably arranged on top of said brackets. Slab rods 14 are arranged to pass over the 85 brackets and over the rings 12 and 13, and through the column as indicated in Fig. 3 of the drawings. The rings 10, 12 and 13 I designate buckle rings as they assist in resisting the tension or tendency of the floor slab to buckle or bend downward. The wires 9 wound around the members of the brackets I designate shear loops, as they tend to 90 resist the shear in the slab.

Each of the brackets 4 forms, in effect, a fixed girder having one free end and, therefore, acting as a cantilever and receiving and transmitting to the column the tension stress of the floor.

The advantages of this construction are that the series of brackets for each column form a column head that is located wholly within the floor slab, thus giving a level and even surface above and below each slab,

110

while at the same time said brackets reinforce the floor slab against the tension and shear stresses and transmit the load or stress directly to the reinforced column. This construction is also very cheap and easy to erect, the brackets and the buckling rings, being formed of wire rods, may be bent to shape on the work, and it is not necessary to provide any especially constructed reinforcement members, the whole reinforcement being secured by means of rods and the bands or rings 7 and 8. The building constructor is, therefore, not required to provide especially constructed reinforcing devices that must be formed or made up at a factory or work shop and brought to the place of erection in a finished state. It is only necessary to provide rods of suitable size and the necessary number of rings 7 and 8 and then with suitable tools the brackets and the rings 10 and 13 may be formed at the place of erection.

The details of the construction may be varied in many particulars without departing from my invention.

I claim as my invention:

1. In a reinforced concrete building structure, the combination with reinforced concrete columns and a floor slab of concrete supported thereby, of a series of closely spaced U-shaped brackets arranged in vertical planes, and extending in a radial direction from each of the column centers into the floor slab, the inner free ends of the brackets being bent to extend longitudinally of the columns and located substantially in the center of the columns, means for engaging the bent ends of the brackets for holding the same together, vertically extending column rods located in each column adjacent the outer face thereof, and rings surrounding said column rods and located above and below the members of the brackets.

2. In a reinforced concrete building structure, the combination with reinforced concrete columns and a floor slab of concrete supported thereby, of a series of closely

spaced U-shaped brackets arranged in vertical planes; and extending in a radial direction from each of the column centers into the floor slab, the inner free ends of the brackets being bent to extend longitudinally of the columns, and located substantially in the center of the columns, means for engaging the bent ends of the brackets for holding the same together, vertically extending column rods located in each column adjacent the outer face thereof, rings surrounding said column rods and located above and below the members of the brackets, and a plurality of buckling rings arranged concentrically of said columns, and located between the upper and lower members of the brackets.

3. In a reinforced concrete building structure, the combination with reinforced concrete columns and a floor slab of concrete supported thereby, of a series of closely spaced U-shaped brackets arranged in vertical planes, and extending in a radial direction from each of the column centers into the floor slab, the inner free ends of the brackets being bent to extend longitudinally of the columns, and located substantially in the center of the columns, means for engaging the bent ends of the brackets for holding the same together, vertically extending column rods located in each column adjacent the outer face thereof, rings surrounding said column rods and located above and below the members of the brackets, a plurality of buckling rings arranged concentrically of said columns and located between the upper and lower members of the brackets, and suitable wires wound about the members of the brackets for forming shear loops.

In witness whereof, I have hereunto set my hand this 14th day of November 1910.

WILLIAM PIERCE COWLES.
